UNITED STATES PATENT OFFICE

2,078,791

ELECTRIC VALVE TRANSLATING CIRCUIT

Helmut Cypra, Berlin-Hermsdorf, Germany, assignor to General Electric Company, a corporation of New York

Application January 16, 1935, Serial No. 2,122
In Germany January 19, 1934

5 Claims. (Cl. 171—119)

My invention relates to electric valve translating circuits and more particularly to such circuits in which the amount of current flowing in the circuit is controlled by controlling the 5 conductivity of an electric valve.

In the case of electrically heated furnaces it has generally been required that the furnace temperature be kept substantially constant within very narrow limits and that it be possible to 10 control the temperature of the furnace by external control means. Heretofore it has been common to control the temperature of the furnace by intermittent cutting in and out of heating elements by means of thermal responsive regulating devices. Such arrangements, however, 15 have the disadvantage that the temperature varies between certain limits. It has been proposed to operate electric heating furnaces by means of grid control rectifiers but such arrangements have not been satisfactory where the alternating current supply system does not provide a 20 neutral conductor. This generally has necessitated the use of a transformer having a capacity sufficient to carry the full output load, or it has 25 been necessary to provide means with an artificial neutral point.

It is an object of my invention, therefore, to provide an improved electric valve translating system which will overcome the above mentioned 30 disadvantage of the arrangements of the prior art and which will be simple and reliable in operation.

It is another object of my invention to provide an improved electric valve translating system in 35 which the amount of current flowing in the system may be controlled by the electric valve by means of a simple control circuit.

It is a further object of my invention to provide an improved electric valve translating system for the control of electric furnaces supplied from a polyphase source not provided with a 40 neutral point.

In accordance with my invention a three-phase furnace is connected in open or closed star arrangement wherein the individual resistors of the furnace are connected directly with the electrodes of grid controlled electric valves. Grid controlled electric valves each having an anode and a cathode or a multi-anode common cathode valve can be used in conjunction with existing three-phase furnaces to provide constant regulation of the temperature without material change in the existing furnaces.

55 The novel features which I believe to be char-

acteristic of my invention are set forth in particularity in the appended claims.

My invention itself, however, both as to its organization and method of operation, together with further objects and advantages thereof, will 5 be better understood by reference to the following description taken in connection with the accompanying drawings in which Fig. 1 shows a three-phase open star furnace connection, Figs. 2, 3, and 4 are explanatory of the method of operation of my invention, Fig. 5 shows an open star connected modification of my invention, and Fig. 6 shows a closed star modification of my invention.

Referring to Fig. 1 of the drawings, I have 15 illustrated therein the application of my invention to a three-phase line 1, 2, 3, supplying current to the resistors 4, 5, 6, of an electric furnace, the ends of which are connected to the anodes of the electric valves 7, 8, and 9. The 20 anode of each of the valves 7, 8, and 9 is connected to the cathode of the adjacent valve so as to form a delta connection. Although any of the valves well known in the art may be used, I prefer to use valves containing an ionizable 25 medium and having a control electrode. The control electrodes of the valves are energized from the three-phase line through any suitable phase shifting arrangement, such for example, as a rotary phase shifting transformer 10 having 30 its secondary winding 11 connected to the control electrodes and cathodes of the valves 7, 8, and 9. The position of the secondary windings 11 with respect to the primary winding 10 of the phase shifting arrangement is determined 35 by the temperature of the furnace by means of an electric motor 12 which is energized from a thermostat 13. The thermostat 13, which is responsive to the temperature of the electric furnace comprising the resistors 4, 5, and 6, may 40 be any one of those common in the art which operates to determine the direction in which the motor 12 will rotate in response to a change in the temperature of the furnace.

For a better understanding of the operation 45 of my invention reference may now be had to Figs. 2, 3, and 4. In these figures the assumption has been made that the grid control of the valve is such that an anode current flows at the beginning of the cycle and the assumption 50 also furthermore has been made for the purposes of explanation that the voltage drop across the valve is negligible. For a complete cycle of alternating current it is convenient to divide the time of the cycle into intervals I to VI. The 55

curves 1', 2', and 3' represent the alternating current voltage phases 1, 2, and 3 of Fig. 1. Thus, in time interval I current flows from phase 1 through the discharge valve 7 to phase 3. It is assumed that the discharge valves 8 and 9 are non-conductive at this instant. The dotted line curve D in time interval I thus is then the potential of the cathode of the discharge valve 7 and also of the anode of the valve 9 when the load devices 4, 5, and 6 are equal and the valves 8 and 9 are non-conductive. During the non-conductive condition of valve 8 the valve 9 is at a potential corresponding to the voltage difference between the phase voltage 2' and the curve 15 D in the first half of the time interval I; and in the second half of the time interval I the valve 8 is at a potential equal to the voltage difference between the phase 2' and the curve D. This causes valve 8 to become conductive so that 20 the electrode potentials of all the discharged valves assume the value given by the line A. Thus during the latter half of the time interval I current is supplied from the phase 2 to the resistor 5 through the electric valve network. Thus 25 each of the dotted line curves B, C, and D represents the potentials of the discharge valves in the instance where only two phases are active, and hence curve B represents the condition when phase 3 is inactive, curve C represents the condition when phase 1 is inactive, and curve D represents the condition when phase 2 is inactive.

During actual operation in the time interval I current flows from phase 1 through valve 7 to phase 3 and through the valve 9 to phase 2, and in the second half of the time interval I current flows from phase 2 through the valves 7 and 8 to phase 3. It will be apparent to those skilled in the art that similar operating conditions obtain in 40 the time intervals III and V. During the time interval IV phase 1' is negative and hence valves 8 and 9 become conductive to transmit current to phase 1 through the load device 4 in a reverse direction. It will furthermore be obvious to those skilled in the art that a similar cycle of operation obtains in time intervals II and VI.

If the currents flowing between two phases in the individual time intervals are combined we may obtain the current flow through each of the load devices 4, 5, and 6 connected to the phases 1, 2, and 3. Fig. 3, therefore, represents the combination of current which indicates the total current and the direction thereof flowing through the load devices, as for example, load device 4. In Fig. 4 the currents have been combined to produce the current carried by valves, for example valve 8. It is apparent from the curve of Fig. 3 that the current does not have a predominant third harmonic present so that no harmonic is introduced into the three-phase system. The step-like shape of the current wave and the fact that the valves are conductive for a phase of 240° are conducive to the reduction of arc backs. The grid control of the valves permits the complete regulation from zero to 100% load of the furnace while maintaining the individual phases of the system symmetrically loaded throughout the control range.

While I have shown the application of my invention to an arrangement wherein a three-phase system supplies energy to an electric furnace, it will be apparent to those skilled in the art that the resistors 4, 5, and 6 could well be the primary windings of transformers or machines. Furthermore, it is also apparent that the ar-

rangement is not limited to three-phase systems but may be used with any number of phases provided that the electric valves are connected in a polygon having as many arms or sides as there are phases. Furthermore, my invention is also applicable to alternating current supply systems not provided with a neutral point.

The arrangement disclosed in Fig. 5 is of particular advantage where it is desired to provide an economical arrangement for a small load or where it is desired to obtain economy by the use of a multi-anode single cathode electric valve. In this figure like parts are designated with the same reference characters as were used in Fig. 1. In this instance, however, the load units or furnace heater resistors 4, 5, and 6 which are connected to the three-phase line 1, 2, 3, are connected to an electric valve 14 to form an open star connection. The valve 14 is provided with a cathode, two anodes and two control electrodes. Two of the load units 4 and 6 are connected to the anodes whereas the remaining load unit 5 is connected to the cathode of the valve 14. In the arrangement disclosed only two of the windings of the phase shifting arrangement comprising the transformer 10 and the secondary windings 11 are utilized to supply energy to the control electrodes of the valve 14. It will be apparent to those skilled in the art that the amount of power flowing through the load devices 4, 5, and 6 may be controlled by means of a shift in the phase of the control electrode excitation of the valve 14 thereby controlling the amount of power transmitted between phase 2 and the remaining phases.

Fig. 6 discloses a modification which is particularly suitable for load circuits such as an existing three-phase load or furnace having a closed star connection where it is desired to obtain regulation without changing the existing connections. Such an arrangement is also advantageous where it is desired to use a multi-anode common cathode valve for regulation and still maintain a symmetrical load on the alternating current system. Thus in Fig. 6 the load consuming devices 4, 5, and 6, which are connected to the alternating current line 1, 2, 3, are joined together in star fashion to form a neutral point which is connected to the cathode of an electric valve 15. The valve 15 is provided with a plurality of anodes which are connected to the alternating current circuit terminals of the load devices 4, 5, and 6. Control elements or grids are provided for each of the anodes to control the discharge of the valve 15. The grids are energized from the alternating current line through a suitable phase shifting arrangement such as a rotary phase shifter comprising the transformer winding 10 and the secondary windings 11 which in turn energize the windings of the transformer 16.

The operation of the arrangement shown in Fig. 6 is such that when all of the grids or control members of the valve 15 are negative so as to prevent discharge through the valve 15 the load system or furnace comprising the load elements 4, 5, and 6 operates as an unregulated system. When one of the anodes is energized and discharge through the valve is possible, the load device connected to that anode is short circuited and the output or current flow in the other two load devices is increased. The maximum output of the furnace or load circuit is obtained when the grid circuit of the valve 15 is of such a phase relation with respect to the anode voltages as to permit complete conduction in each cycle of alter-

nating current. Under these conditions, at any one instant one resistor is always short circuited, whereby the current flow through each of the other two resistors or load devices is equal to three times the unregulated current value. With such an arrangement the furnace may be regulated from 100% to about 240% of the normal current output of an unregulated furnace.

While the arrangement disclosed in Fig. 6 has been shown as applied to a three-phase system it will be obvious that such an arrangement can be applied to any polyphase star connected load circuit provided that additional anodes and control electrodes are supplied in the controlling 15 electric valve.

While I have shown and described my invention in connection with certain specific embodiments, it will, of course, be understood that I do not wish to be limited thereto, since it is apparent 20 that the principles herein disclosed are susceptible of numerous other applications, and modifications may be made in the circuit arrangement and in the instrumentalities employed without departing from the spirit and scope of my invention as set forth in the appended claims.

What I claim as new and desire to secure by Letters Patent of the United States is:

1. In an electric valve translating system, the combination of a source of alternating current of n phases, n load devices each connected at one end to a different phase, a plurality of electric valves containing an ionizable medium, and means for controlling the conductivity of said valves, said valves inter-connecting said load devices to provide n control electric discharge paths between said devices so that the conductivity of any one of said valves will cause current to flow through two of said devices.

2. The combination, in an electric valve translating apparatus, of a source of alternating cur-

rent of n phases, n load devices each connected at one end to a different phase, a plurality of electric valves containing an ionizable medium, and means for controlling the conductivity of said valves, said valves interconnecting the other ends of said load devices so that the conductivity of any one of said valves will cause current to flow through two of said load devices.

3. In an electric valve translating apparatus, the combination of a source of alternating current of n phases, n load devices each connected to a different phase, n electric valves connected between said load devices and directly to each other in a polygonal network of n sides, and means for controlling the conductivity of said valves thereby to control the current to said load devices.

4. In an electric valve translating system, the combination of a source of alternating current of n phases, n load devices arranged to form a star connected network in direct conductive relation to the phases of said alternating current source, n electric valves containing an ionizable medium and being connected across said load devices, and means for controlling the conductivity of said valves thereby to control the current flow to said load devices.

5. The combination, in an electric valve translating system, of a source of alternating current of n phases, n load devices each arranged in conductive relation to a different one of said phases, a plurality of electric valves each containing an ionizable medium, and means for controlling the conductivity of said valves, said valves being connected directly to each other and to said load devices whereby the conductivity of one of said valves causes current to flow through two of said load devices.

HELMUT CYPRA. 40
